TENS-TRANSFER MECHANISM

Vito Viola, Oakland, and Cecil Olson, El Cerrito, Calif., assignors to Friden, Inc., a corporation of California

Filed Nov. 2, 1959, Ser. No. 850,184

3 Claims. (Cl. 235—133)

This invention relates to an improved auxiliary, or outboard, tens-transfer mechanism for a calculating machine of the Thomas-type, such as disclosed in U.S. Patent No. 2,229,889, issued to Carl M. F. Friden on January 28, 1941.

Heretofore, in calculating machines having a shifttable accumulator, or register, carriage in which a plurality of ordinally arranged register wheels are mounted, certain of such wheels will be positioned to the right and/or left of the stationary portion of the machine in any shifttable position of the carriage. Within the stationary portion of the machine, an ordinal selection mechanism, an actuating mechanism, and a tens-transfer mechanism are located to effect registration of values in those register wheels aligned with the selection mechanism. In order to effect a tens-transfer in the register wheels positioned to the left of the selection mechanism, an auxiliary tens-transfer mechanism is provided and comprises a series of tens-transfer disks, one for each wheel, and a control means therefor. In a machine having a ten-order selection mechanism, commonly referred to as a "ten-bank" machine, a tens-transfer into those register wheels aligned with the selection mechanism and into the two next higher order wheels is under the control of the tens-transfer mechanism in the stationary portion of the machine. In the type of calculating machine referred to and described herein, the ordinal register wheels aligned with the selection mechanism, together with the two next higher order wheels, will hereinafter be referred to as the "inboard" orders, while those wheels to the left thereof will be referred to as the "outboard" orders.

Each of the disks of the auxiliary tens-transfer mechanism is provided with a peripheral notch which is adapted for engagement by a corresponding one of a series of ordinal actuator fingers secured on an axially adjustable shaft rockably mounted in the accumulator carriage. The actuator fingers are angularly offset in a staggered relationship axially of the shaft and become effective, during a subtractive operation and upon rocking of the shaft, to successively enter the notch in the disk associated with the lower outboard order wheel if the wheel registers "0" and the notch in each disk associated with the adjacent higher order wheels which register "0." Similarly, if during an additive operation each of the outboard order wheels register "9" and a tens-transfer is effected through the highest inboard order, the actuator fingers will enter the notch of the disks associated with the outboard order wheels. Following the entry of the fingers into the notches of the corresponding disks, the shaft is axially adjusted in one direction or the other to effect a simultaneous tens-transfer in all outboard order accumulator wheels. As the carriage is shifted to the right, each of the auxiliary tens-transfer disks, upon movement of the disk inboard of the machine, is axially moved to an inactive position out of the rotational plane of the corresponding actuator finger.

Heretofore, in auxiliary tens-transfer mechanisms of this type, the rocking of the actuator fingers was under the control of a torsion spring which permitted a limited rocking movement of the actuator finger shaft. Thus, the angular displacement between adjacent actuator fingers was critical and had to be held to a minimum to assure the active positioning of all the fingers.

It is, therefore, an object of the present invention to

2

provide an improved auxiliary tens-transfer mechanism for a calculating machine.

It is another object of the present invention to provide independently operable tens-transfer actuator members in an auxiliary tens-transfer mechanism for use in a calculating machine.

Another object of the present invention is to provide an improved tens-transfer control mechanism for each outboard order of a calculating machine.

A further object of this invention is the provision, in a calculating machine, of an improved auxiliary tens-transfer control mechanism in which the independently operable actuators associated with the outboard orders are successively disabled when ordinally shifted inboard of the machine.

Still another object is to provide an improved auxiliary tens-transfer mechanism for a calculating machine whereby a tens-transfer into the outboard orders of the machine is controlled by the highest inboard order irrespective of the ordinally shifted position of the carriage.

Further objects and advantages will become apparent from the following description of a preferred embodiment of the present invention which is shown in the accompanying drawings in which:

25 FIG. 1 is a top plan view of a calculating machine incorporating an outboard tens-transfer mechanism exemplifying the invention;

FIG. 2 is a fragmentary sectional plan view of the actuating and tens-transfer mechanism for the inboard orders 30 of the machine, with the accumulator carriage and a portion of the selection and actuating mechanism in certain orders omitted to better illustrate the construction;

FIG. 3 is a partial cross-sectional elevational view showing an outboard tens-transfer actuator, or bail, and 35 the actuating mechanism therefor, the view being taken as indicated by the line 3—3 of FIG. 1;

FIG. 4 is a sectional elevational view of the nine outboard tens-transfer actuators, or bails, as viewed from the left in FIG. 1, and showing the relative angular displacement of the actuating fingers;

FIG. 5 is a front elevational view showing the outboard orders of the accumulator register in the shifttable carriage and the auxiliary tens-transfer actuating mechanism therefor, the view being taken as indicated by the lines 5—5 of FIG. 3;

FIG. 6 is a fragmentary sectional plan view of the accumulator register showing certain orders thereof, and the tens-transfer actuators associated therewith, the view being taken as indicated by the line 6—6 of FIG. 5; and

50 FIG. 7 is an isometric view of one of the tens-transfer actuators, or bails.

The invention as described herein is preferably incorporated in a calculating machine of the Thomas-type, such as that shown in the above-mentioned Friden patent, No. 2,229,889. It is not intended that its use should be limited only to a machine of this construction, since it is evident that the underlying principles thereof may be advantageously applied to other types of calculating machines.

60 The mechanism which is conventional in the machine of the above-mentioned patent will not be described herein, unless necessary to provide a more complete understanding of the mechanism of the present invention. The calculating machine to which the invention is particularly adapted, generally includes a body in which the selecting, actuating, and tens-transfer mechanisms are mounted, and a shifttable accumulator carriage, which also supports a part of the tens-transfer mechanism.

65 In the preferred embodiment of our invention disclosed herein, the body of the calculating machine includes a base (not shown) having a cover 11 (FIG. 1) and right and left side frame members 12 and 13, respec-

tively, mounted thereon (FIG. 2). Between the respective side frames 12 and 13 there is provided a plurality of transverse frame members including a front bearing plate 14, a center bearing plate 15 and a rear bearing plate 16 which serve to support various parts of the operating mechanism referred to hereinafter.

The register carriage 20 (FIGS. 1, 3 and 5) is mounted in a well-known manner for endwise shifting movement within the framework of the machine and under the control of a conventional power-driven mechanism. The shifting movement of the carriage in either direction may be selectively controlled by a depression of one or the other of a pair of manually operable shift keys 17 and 18, or may be automatically controlled by certain function control mechanisms which are customarily provided in machines of this character.

Provided within the carriage 20 is a plurality of ordinarily arranged accumulator numeral wheel shafts 21, which shafts are suitably journaled in the carriage frame bar 22. At its upper end, each shaft 21 carries a numeral wheel 23 having the digits from "0" to "9" inscribed thereon, and at its lower end carries a ten-tooth gear 24. Each numeral wheel 23 is rotatable in either direction to register positive or negative values and for this purpose, gear 24 (FIGS. 2 and 3) has associated therewith a pair of opposed bevel gears 28 and 29 formed on the respective ends of spool 30, slidably and nonrotatably mounted on the square selection shaft 31. At its ends each square shaft 31 is suitably journaled in the front plate 14 and the rear plate 16 and intermediate its ends in plate 15. The spools 30 and associated gears 28 and 29 are shiftable in either direction relative to the corresponding gear 24 by a transversely extending plus-minus gate strap 32 positioned between each pair of gears and supported at its ends by similar arms 33, which arms are secured on gate shaft 34 journaled for rocking movement in side frame members 12 and 13. Thus if the gate 32 is rocked (counter-clockwise in FIG. 3), the gears 28 will enmesh with the corresponding accumulator gears 24 to effect an additive registration on the numeral wheels 23. Conversely, if the gate is rocked clockwise, the gears 29 will enmesh with the corresponding accumulator gears 24 and a subtractive registration will be effected. The rocking of the gate 32 may be selectively controlled in a well-known manner by the depression of a plus key 35 or a minus key 36 (FIG. 1).

It can be seen from the above description that an increment of movement of a spool 30 will be transmitted to its associated accumulator wheel 23 following the engagement of either of the gears 28 or 29 with the corresponding gear 24. Means are provided in the various orders of the machine to determine the number of increments of such movement. For this purpose, a plurality of numeral, or value, keys 38 is provided for each order of the machine (FIG. 1). The numeral keys 38 in each order cooperate conventionally with a pair of differential value selection slides 39 and 40 (FIG. 2), which are mounted for endwise shifting movement and are differentially set in accordance with the values of the depressed value key. Selection slide 39 is associated with the numeral keys 38, determining values from "6" to "9," and the slide 40 is associated with the numeral keys 38, determining values from "1" to "5." At their rearward ends, each of the selection slides 39 and 40 is operatively connected to a pair of selection gears 41 and 42, respectively, which gears are slidably but nonrotatably mounted on the square shafts 31. Each selection gear 41 and 42 is provided with ten teeth and is arranged to cooperate respectively with the teeth of the stepped tooth actuators 43 and 44. The square shafts 31 are ordinarily arranged longitudinally of the machine in accordance with the ordinal arrangement of the keys 38 and the register wheels 23. In each adjacent pair of the transversely spaced orders of the selection mechanism, there is provided a single longitudinal actuator shaft 46 on which each pair of

stepped tooth actuators 43 and 44 for the respective orders is secured. Accordingly, the square selection shafts 31 of each of the adjacent pair of orders are spaced to either side of, and above, the associated actuator shaft 46 (FIG. 2). At its forward end, each of the actuator shafts 46 is journaled in the transverse bearing plate 14 and at its rearward end is journaled in the auxiliary crossframe member 47 spaced from, and secured on, bearing plate 15. Adjacent the forward end thereof, each of the actuator shafts 46 carries a bevel gear 48 meshing with a similar bevel gear 49 secured on the main drive shaft 50 which extends transversely of the machine and is journaled in side frame members 12 and 13.

In the embodiment shown, a conventional source of power is provided in the form of an electric motor which serves through a well-known cyclically operable clutch means to impart one rotation to the main drive shaft 50 for each cycle of machine operation. Thus, for each rotation of the main drive shaft 50, the actuator shafts 46 and corresponding stepped tooth actuators 43 and 44 will receive a single rotation to cause a registration of the number selected by the depressed value key, or keys, 38 in the associated accumulator register wheels 23. Each pair of stepped tooth actuators 43 and 44 is mounted in angularly offset relation on the corresponding actuator shaft 46 and also relative to the stepped tooth actuators associated with the adjacent higher order. The arrangement is such that the teeth of the actuators 43 and 44 associated with the units order, i.e., the rightmost order in FIG. 2, become active first, followed by the teeth of the actuators 43 and 44 associated with the tens order and the other orders in succession thereafter.

Conventional means are provided for preventing overthrow of the register numeral wheels upon termination of an actuation thereof. For this purpose, the stepped tooth actuators 43 and 44 of each pair of actuators are so positioned on the corresponding actuator shaft 46 that their last active teeth are in alignment, and the Geneva wheel 55 (FIG. 2) carried by each square selection shaft 31 cooperates with the locking disk 56 on the associated actuator shaft 46. Each Geneva wheel 55 has ten concave faces, the actively positioned one of which is engaged by the associated locking disk 56 immediately following actuation of either gear 41 or 42 by the last active tooth of the respective corresponding actuator 43 or 44. Consequently, the associated shaft 31 and associated numeral wheel 23 are positively locked against further rotation. Since this mechanism forms no part of the present invention, the foregoing description is believed to suffice. However, for a more complete disclosure, reference is to be had to the aforementioned Patent No. 2,229,889.

Machines of the type presently being described are generally provided with six actuator shafts 46 and twelve square shafts 31. The first five actuator shafts 46 (from the right in FIG. 2) carry the stepped tooth actuators 43 and 44 cooperating with the respective pairs of adjacent shafts 31 associated with the ten orders of the selection mechanism to control the registration of a value placed in the keyboard into the register wheels 23. The leftmost actuator shaft 46 (FIG. 2) cooperates with the remaining pair of square shafts 31 to control a tens-transfer from the tenth order into the eleventh and twelfth orders of the accumulator register. Thus, the twelfth order numeral wheel 23 (from the right-hand end of the accumulator carriage 20) is normally the highest order wheel to receive a tens-transfer impulse from the conventional tens-transfer mechanism, when the carriage is in its leftmost position. Hence as stated hereinbefore, inasmuch as the conventional tens-transfer mechanism is mounted within the stationary portion of the machine and is contained in the space existing between the right and left side frames of the machine, the first twelve orders of the register (FIG. 1) may be considered to be the inboard orders thereof when the register carriage is in

its leftmost end position, whereas all higher orders of the register may be considered to constitute the outboard orders of the register.

Generally, the tens-transfer mechanism associated with the selection mechanism cooperates with the actuator shafts 46 in a well-known manner and comprises tripping means associated with each numeral wheel, except that of the highest order wheel, and is controlled by a lower order wheel to enable a drive connection from a tens-transfer actuator to the numeral wheel of the next higher order, so that such next higher order numeral wheel receives one increment of movement when the lower order numeral wheel passes from "9" to "0" or "0" to "9". The sign character of the transferred increment is determined in the same manner as the sign character of the digitation, i.e., by the meshing engagement of the gears 28 or 29 of spools 30 with the corresponding gears 24.

To effect the tripping of a tens-transfer, each numeral wheel shaft 21 (FIGS. 2 and 3) is provided with a tens-transfer cam 60 positioned immediately below the carriage frame bar 22. Each cam 60 cooperates with the corresponding tripping, or tens-transfer, lever 61 pivotally mounted in the frame bar 22 by means of stud 62, which is secured to the tens-transfer lever 61 and is journalled in a bore (not shown) provided in the frame bar. The tens-transfer lever 61 has nose 63 positioned in the path of the transfer cam 60 of one order, so that when the numeral wheel 23 passes from "9" to "0," or from "0" to "9," the nose 63 is engaged by the cam 60 and the lever 61 is rocked in a counter-clockwise direction, as viewed in FIG. 2. The limit of such movement is determined by the engagement of the face of the nose 63 with the next adjacent transfer lever 61. Each lever 61 is also provided with arm 64 extending into the next higher order of the machine and normally engaging the lever 61 of the next order adjacent its pivot stud 62. The formed-over ear 66 at the end of the extended arm 64 (FIG. 2) lies between a pair of annular flanges 67 formed on hub 68 of a tens-transfer gear 69. Hub 68 and gear 69 are slidably, but nonrotatably, mounted on the square shaft 31, so that rocking movement of the tens-transfer lever 61 by a lower order numeral wheel 23 results in shifting the hub 68 and gear 69 in the adjacent higher order, forwardly of the machine to position the gear 69 in operative relation with respect to the tens-transfer actuator therefor. Single tooth tens-transfer actuator 71 for tens-transfer gear 69 is spaced from, and secured with, the tens-transfer actuator 72 of the adjacent lower order by suitable studs 73 to the locking disks 56.

From the above description it is seen that each time a tens-transfer is determined in one order of the machine, the tens-transfer gear 69 of the next higher order is moved into active position to be subsequently operated by the associated tens-transfer actuator 71 or 72. Means are provided for resiliently maintaining the tens-transfer gears 69 in either shifted position thereof, and associated with the maintaining means is a restore cam which cooperates with each pair of adjacent tens-transfer gears 69. The rearmost annular flange 67 of each gear hub 68 extends between spaced annular flanges 78 of the corresponding stub shaft 79 which is slidably mounted in the crossbar 47 and auxiliary transverse member 80, spaced from, and secured to, the crossbar 47. Each shaft 79 is provided with two annular grooves for cooperation with a spring-urged ball detent mounted in the transverse member 80, all of which is conventional and is not shown. Thus, the shafts 79 and transfer gears 69 are maintained resiliently in either the rearward inoperative position or in their forward operative position. Referring to FIG. 2, when a gear 69 is shifted to the operative position, the forward end of the associated shaft 79 will project beyond the crossbar 47 into the path of the restore cam 81 integrally formed with, and arcuately offset from, the rearmost tens-transfer actuator 72 of each pair of associated tens-transfer actuators. As seen in FIG. 2, each pair of

shafts 79, for adjacent orders of the machine, is spaced closer together than the spacing between the orders, so that both shafts 79 of each pair lie in the path of a single restoring cam 81. The cams 81 are successively operative to restore each operatively positioned shaft 79 and associated gear 69 to the inoperative position thereof following a tens-transfer operation in the corresponding order.

A similar tens-transfer actuator construction is provided for all orders, including the two highest inboard orders, i.e., the eleventh and twelfth orders of the machine, thereby enabling a tens-transfer into these orders. It is to be noted in FIG. 2 that although there are two tens-transfer actuators 71 and 72 shown on the right-hand actuator shaft 46, only that actuator associated with the tens-transfer gear 69 in the tens-order is necessary, since no tens-transfer occurs in the units order. It will also be noted that the tens-transfer actuators 71 and 72 on each actuator shaft 46, as well as the successive pairs of actuators 71 and 72 on adjacent actuator shafts 46, are angularly displaced to provide for operation of the tens-transfer actuators seriatim from the lowest, or tens, order to the highest order.

Briefly, assuming that a tens-transfer has been determined by shifting two of the transfer gears 69 in adjacent orders to active position, the corresponding tens-transfer actuators 71 and 72 will have rotated from their full-cycle position to a position where the rearward actuator 72 is positioned to impart a one-tenth rotation to the associated gear 69 to enter the transferred increment into the corresponding numeral wheel. Subsequently, the other, or forward, actuator 71 will become effective with respect to its associated tens-transfer gear 69 to cause one-tenth of a rotation thereof and complete the tens-transfer into the associated numeral wheel. The forward actuator 71, in effect, trails behind the rearward actuator 72 a sufficient angular distance to accommodate the setting of the tens-transfer mechanism in the adjacent higher order by movement of the gear 69 to active position if the transferred increment placed in the adjacent lower order numeral wheel associated with this gear 69 determines a tens-transfer operation into the next higher order numeral wheel.

Various auxiliary tens-transfer mechanisms have been used heretofore in machines of the type described herein to complete a tens-transfer operation into the outboard orders of an accumulator register. One of such mechanisms functions in a manner somewhat similar to that of the invention presently to be described. However, it has been found that there are several limitations in the application of this particular prior art mechanism, which limitations will become apparent during the progression of the following brief description thereof.

In an eight-bank machine in which the prior art mechanism is incorporated, the main tens-transfer mechanism in the machine is effective to cause a transferred increment into the two dials in the register that lie to the left of the keyboard, or selection mechanism. The eight dials in the register which are aligned with the keyboard orders, together with the two dials to the left thereof, are commonly referred to as the "inboard" orders of the machine, while those ordinal dials to the left thereof are referred to as the "outboard" orders.

For the auxiliary tens-transfer mechanism associated with the outboard orders of the machine, a bail is mounted for endwise movement on a shaft secured within the accumulator carriage. Movement of the bail in one direction or the other determines the sign character of the registration in the accumulator dials and is under the control of a manually operated lever. It is necessary, therefore, that the sign character control lever be manipulated prior to each machine operation to assure the correct sign character of a registration. A quill shaft is also carried by the bail shaft rockably mounted thereon and restrained between the legs of the bail for endwise movement therewith.

A series of ordinarily arranged tens-transfer actuators are secured on the quill shaft for cooperation with corresponding notched disks associated with the outboard orders of the register. Each disk is slidably mounted on the corresponding dial shaft, including the tenth order, or highest, inboard order dial shaft, and is normally urged to an active position for cooperation with the associated tens-transfer actuator. Within one face of each disk there are ten equiangularly spaced recesses, nine of which are shallow, while the tenth is in the form of a notch in the periphery of the disk. The leading edge of the cam portion of each tens-transfer actuator is angularly offset relative to the adjacent actuator, thereby forming a spiral axially of the quill shaft and the trailing edges of the cam portion of the actuators are axially aligned. Thus, the cam portion of the actuator associated with the highest inboard order is the broadest, while that associated with the highest outboard order is the narrowest.

In prior art auxiliary tens-transfer apparatus, a torsion spring serves to rock the quill shaft and the tens-transfer actuators thereon so that with the carriage in its leftmost position and following the manual setting of the bail and actuators for addition, the actuator associated with the highest inboard order and those associated with all higher outboard orders will be rocked into the notch of the disk associated with the corresponding ordinal dials if these dials register "9." Conversely, if the auxiliary mechanism is first conditioned for a subtractive registration and the dials register "0," each of the tens-transfer actuators will be rocked into the notch in the corresponding dials.

The rocking movement of the tens-transfer actuators is restrained by a blocking member which is rocked out of the way in timed relation to the digitation phase of each machine operation, thereby enabling the function of the torsion spring. The blocking member also serves to restore the tens-transfer actuators at the end of the operation. Following the rocking of the actuators to active position, an increment of rotation of the tenth, or highest, inboard order will serve to move the quill shaft axially, thereby imparting an increment of rotation to each of the higher outboard orders. If, during an additive or subtractive operation a "9" or "0" is not registered in an outboard order dial, the actuator associated with that order and the actuators associated with the order dials to the left thereof will be blocked from entry into the notch of the corresponding dials.

As each order dial with which the auxiliary tens-transfer mechanism is associated is moved inboard of the machine, the corresponding disk is rendered inactive by movement thereof, out of the rotational plane of the associated actuator. The last dial to be moved inboard becomes the highest inboard order dial and is effective to cause axial translation of the quill shaft when the dial passes from "9" to "0," or "0" to "9," thereby causing an incremental rotation of the higher order dials with which the associated actuators are engaged.

Prior art auxiliary tens-transfer mechanisms of the type described above have been found to be unsatisfactory when there are more than six outboard orders involved. Inasmuch as the rocking of the actuators is under the control of the torsion spring, the angular displacement between the leading edge of adjacent actuators must be held to a minimum to assure the possible engagement of the highest order actuator into the notch of the disk associated with the corresponding dial. For each additional actuator employed, the angular displacement between actuators becomes even more critical, and with the addition of two or more actuators, the rocking movement thereof by means of a torsion spring is impractical. The space requirement negates the use of a torsion spring of sufficient size to effect an engagement of the leftmost of eight or more outboard order actuators with the corresponding ordinal disks. The increased angular rocking movement of the quill shaft necessary for the operation of two or

more additional actuators renders the rockable restore bar for the actuators inoperative since, upon movement of the actuators to active position, the axially aligned depending portions of the actuators are moved to a position out of the arcual path of the restore bar. Because of the spatial limitation in the machine and the shifting movement of the carriage, the restore mechanism for the actuators of well-known auxiliary tens-transfer devices is not adaptable to machines having eight or more effective outboard orders.

Considering the above-described prior art in view of the following detailed description of the present invention, it will be seen that the present invention is adapted to overcome many of the objectionable features found in the prior art.

In order to extend the increment transfer from one order of the register to the next higher order thereof beyond the twelfth, or highest, inboard order numeral wheel 23, the machine shown and described herein is provided 20 with an auxiliary, or outboard, tens-transfer mechanism, which enables tens-transfers to be effected throughout the entire capacity of the register.

When the register carriage 20 occupies its leftmost position, the main, or convention, tens-transfer mechanism, described hereinbefore, is adapted to effect an incremental transfer into the twelfth order numeral wheel 23. Assuming now that the numeral wheels 23 in the carriage 20 register "0" and that the "1" value key 38 in the first, or units, ordinal row of keys (FIG. 1) is depressed, the tens-transfer phase of a subtractive machine 30 operation is not terminated with an incremental transfer into the twelfth order dial, but is fully carried to all the higher outboard order dials by means of an auxiliary tens-transfer mechanism under the control of the twelfth, or highest, inboard order dial.

The present invention for controlling a tens-transfer into each of a predetermined number of the outboard ordinal accumulator dials 23 in the register carriage, utilizes a series of independently rockable tens-transfer bails, or actuators, 102, 103, 104, 105, 106, 107, 108, 109 and 110 (FIGS. 3, 4, 5, 6 and 7). All of these bails are adjacently mounted in an ordinal arrangement on a rod, or shaft 111, supported for endwise movement in brackets 112 and 113 secured on the carriage frame 22, by similar screws 114 and 115, respectively. The actuators 102 to 110, inclusive, cooperate respectively with the highest inboard, or twelfth, order dial and the successive higher outboard order dials. Each of the dial shafts 21 for these orders, i.e., the twelfth to the twentieth order, inclusive, carries a disk 118 secured thereon, which disk has nine open-end recesses, or indentations, 119 in the lower face thereof and a peripheral notch 120. The recesses 119 and notch 120 are equiangularly spaced and, in essence, form the teeth of a gear. In the "0" registering position of a dial 23, the notch 120 is to the right of the vertical center line, as seen in FIG. 6, whereas, in the "9" position of a dial 23, the notch 120 is one tooth-space removed in a clockwise direction.

Each of the tens-transfer bails 102 to 110, inclusive, is formed in a somewhat similar manner, having legs 121 and 122 disposed in a parallel plane at a right angle to a bar 123 at the respective ends thereof.

The arrangement of the bails is such that the leg 121 of a bail associated with a higher order is contiguous with the leg 122 of the bail of the adjacent lower order, so that the leading edge of an upwardly extended lug 124 on each leg 121 is normally in engagement with a formed-over ear 125 on the leg 122 of the adjacent lower order bail, as seen in FIG. 6. Inasmuch as the bail 102 is the rightmost bail, the leg 121 thereof does not carry a lug 124. In addition to the lug 124, the leg 121 of each of the bails 102 to 110, inclusive, is provided with an arcuately formed finger 126, the arcual surface of each of which is of an incrementally shorter extent than that 70 of the finger 126 of the adjacent lower order bail (FIG. 5).

4). The lower portion of each finger 126 is beveled to provide a chamfered surface which engages with a flat surface provided within the carriage frame 22 and serves as a limit stop for the corresponding bail, when rocked counter-clockwise (FIG. 3) to the inactive position thereof. The upper radially disposed edges of the arcuate fingers 126 of bails 102 to 110, inclusive, are equiangularly displaced relative to each other, forming a helix circumferentially about the shaft 111.

The juxtapositioning of the tens-transfer bails 102 to 110, inclusive, on shaft 111 is maintained by means of clips, or collars, 131 (FIGS. 5 and 6) so that axial translation of the shaft 111 will effect a simultaneous adjustment laterally into either of two positions for additive, or subtractive, registrations, as will be described hereinafter. In the condition stated above, wherein the highest inboard order dial 23 and all higher outboard order dials register "0," axial translation of the shaft 111 to the right, to the subtractive position shown in FIG. 6, positions the actuating finger 126 of each bail for entry into the notch 120 in the corresponding disk 118 upon clockwise rocking movement of the bails (FIGS. 3 and 4).

In the normally inactive position of the bails, the radial edge of the finger 126 of bail 102 lies immediately beneath the lower face of the corresponding disk 118, whereas the angular disposition of the radial edge of the finger 126 of each higher order bail relative to the corresponding disk 118 is incrementally greater than that of the adjacent lower order bail. In recalling the correlation between the juxtaposed bails 102 to 110, inclusive, it becomes apparent that a counter-clockwise rocking movement of the bail 102, as viewed from the right in FIG. 6, will cause a similar rocking movement to be imparted simultaneously to all higher order bails. Due to the equiangular displacement of the radial edges of the fingers 126 relative to each other, it also becomes apparent that the finger 126 of bail 102 will enter the notch 120 in the disk 118 associated with the twelfth order dial 23, followed by the entry, serially, of the fingers 126 of the succeeding higher order bails into the notch 120 of the disk 118 associated with the corresponding higher order dials 23.

If the twelfth order dial 23 and all higher order dials are adjusted to register "9," the notch 120 in each associated disk 118 will be positioned one tooth-space in a clockwise direction from the position shown in FIG. 6, or to the left of the vertical center line in this figure. Assuming again that the carriage 20 is in its leftmost shifted position and that the shaft 111 and the bails thereon are in the axially translated leftmost, or additive, position, the actuating fingers 126 of the bails, when rocked, will engage in the notch 120 of the corresponding disks.

Referring now to FIG. 4, each of the legs 122 of the bails 102 to 109, inclusive, is provided with an angularly extended actuating arm 127, all of which arms are in registry lengthwise of the shaft when the bails are in the inactive position shown. To resiliently maintain the bails in the inactive position, the leg 122 of bail 110 carries a laterally extended pin 132 which supports one end of a spring 133, the other end of which is secured on the carriage frame. Spring 133 normally urges bail 110 counter-clockwise (FIGS. 3 and 4) and, by virtue of the overlapping relationship of the lug 124 on each higher ordinal bail with the ear 125 on the adjacent lower order bail, each of the bails is likewise urged counter-clockwise to the inactive position.

As stated above, the sign character of incremental transfers into the outboard order dials 23 is determined by the axially adjusted position of the bail shaft 111. To permit the endwise adjustment of the shaft 111, the depending arm of each bracket 112 and 113 supporting the respective ends of the shaft is positioned intermediate the legs 121 and 122 of the respective bails 110 and 102. In order to control the lateral adjustment of the bails

102 to 110, inclusive, relative to the corresponding disks 118, the left end of shaft 111 is journaled in the vertically disposed arm of a bracket 134 secured on the horizontally extended leg of a setting slide 135 having a substantially L-shaped cross-section. As seen in FIGS. 3 and 5, setting slide 135 is mounted for endwise movement on the lower forward portion of the carriage frame 22 by pin-and-slot connections 137 and carries a series of depending lugs 136 spaced in accordance with the ordinal arrangement of the dials 23. The slide 135, and therefore shaft 111 and tens-transfer bails 102 to 110, inclusive, are resiliently maintained in either the subtractive position shown in FIG. 5, or the opposed, or leftmost, additive position. For this purpose, a three-armed lever 140 is pivotally mounted on a stud 141 carried on carriage frame 22. At its extremity, the depending arm 142 of lever 140 is provided with a bifurcation engaging a pin 143 on the left end of setting slide 135. A pin 144 on the free end of the second, or intermediate, arm 146 of three-armed lever 140 is provided with an annular groove in which one end loop of a substantially circular torsion spring 147 is engaged, the other, or offset, loop of spring 147 engaging in an annular groove of a pin 148 on carriage frame 22. Upon passage of the pin 144 below center, as seen in FIG. 5, spring 147 retains the third, or upwardly, extended arm 149 in engagement with a limit stop pin in the form of the head of a bolt 151. Conversely, upon movement of the slide 135 to the left, to the additive position determined by the engagement of the arm 149 with the head of bolt 152, similar to the limit stop 151, wherein slide 135 is retained by spring 147.

As explained hereinbefore, and as conventional with machines of the type described, upon initiation of a machine operation, the sign character of registration in the register dials 23 is selectively controlled by an adjustment of the plus-minus gate 32 (FIGS. 2 and 3). In addition to controlling the sign character of registrations into the inboard order dials 23, the adjustment of the plus-minus gate 32 also serves to effect a similar adjustment of the setting slide 135 to control the sign character of registrations of a transferred increment into the outboard order dials. The ordinarily arranged lugs 136, one for each outboard order of the register, extend downwardly from the forward edge of the horizontally disposed portion of the slide 135 and parallel to the vertical portion thereof, providing a channel within which the vertical offset end of an upright lever arm 156 is normally disposed. Lever arm 156 is secured on a hub 157 rockably and slidably mounted on a shaft 158 which is supported at its rearward end in a bracket 159 and at its forward end in a bracket 161. The brackets 159 and 161 are secured on side frame member 13 by respective screws 162 and 163 and serve to retain shaft 158 in a plane parallel to frame member 13. A lever arm 164, similar to arm 156, is carried by a hub 166 rockably mounted on a reduced diametral portion of hub 157 in a manner such that each lever arm 156 and 164 may be rocked independently of the other, but are slidable as a unit on shaft 158.

The upper end portion of the lever arm 164 is offset oppositely to that of the lever arm 156 (FIGS. 3 and 5) and is formed inwardly toward, and is spaced from, the offset end of lever arm 156 for oscillation relative to each other in parallel planes. The spacing between the planes of oscillation of the respective offset ends of levers 156 and 164 is sufficient only to permit the passage of the lugs 136 therebetween upon shifting movement of the carriage. At its extremity each of the lever arms 156 and 164 is provided with an ear formed outwardly at a right angle thereto, for selective cooperation with the adjacent lug 136 of setting slide 135 in any shifted position of the carriage. In the normal position of the lever arms 156 and 164, as seen in FIG. 5, the arms are angularly displaced so that the spacing between the ears at the extremity of the respective arms is such that one ear will

engage the adjacent lug 136 in one adjusted position of the slide 135 and the other ear will engage the adjacent lug 136 in the other position of the slide 135 following the lateral movement of the arms 156 and 164.

Referring now to FIGS. 3 and 5, the setting slide 135 is shown in its subtractive position wherein a forward axial movement of the arms 156 and 164 (to the right in FIG. 3) will position the ear of the arm 156 for engagement with the adjacent lug 136. Similarly, if the slide 135 is in its additive adjusted position (to the left in FIG. 5), the adjacent lug 136 will be positioned for engagement by the ear of the arm 164 following a rearward axial movement of the arms 156 and 164 (to the left in FIG. 3). A subsequent scissorlike oscillation of arms 156 and 164 will render either arm 156 operative to move the slide 135 from the subtractive to the additive position, or arm 164 operative to move the slide from the additive to the subtractive position shown in FIG. 5.

As stated hereinbefore, the sign character of registration in the inboard order dials 23 of the register is determined, upon initiation of an operation or during the progress of a plural order operation, by the adjustment of the plus-minus gate 32. Similarly, the sign character of registration in the outboard order dials 23 is determined by the adjustment of the setting slide 135 under the control of the oscillating lever arms 156 and 164. In order to ensure registrations of like sign character in both the inboard and outboard order dials 23, a bellcrank 167 (FIG. 3) is provided, pivoted at 163 on side frame member 13. A lateral projection is formed at a right angle to the upper extremity of the upright arm 169 of bellcrank 167 and pivotally supports a roller 171, adjacent the underside thereof, positioned diametrically between lever arms 156 and 164. The other arm 170 of bellcrank 167 carries a pin 172 engaged in a bifurcation in the free end of an arm 173 secured on the plus-minus gate shaft 34. It, therefore, becomes apparent that upon a counter-clockwise rocking movement of the shaft 34 and plus-minus gate 32 to engage the gears 28 with the corresponding dial shaft gears 24 for an additive registration, arm 173 imparts a clockwise rocking movement to the bellcrank 167, thereby moving the ear at the extremity of the lever arm 156 into its active position relative to the adjacent lug 136 on slide 135. In a like manner, a clockwise rocking movement of the shaft 34 and plus-minus gate 32 to condition the machine for subtraction, effects a counterclockwise rocking movement of the bellcrank 167 to actively position the ear at the extremity of lever arm 164 relative to the adjacent lug 136.

Following the lateral adjustment of the lever arms 156 and 164, means become effective to impart an oscillatory motion to the arms to enable a correct adjustment of the setting slide 135. For this purpose, a bail 176 (FIGS. 3 and 5) is rockably mounted at its one end on shaft 158 and at its other end in an annular groove in a hub 177 of a bellcrank 178, also rockably mounted on shaft 158. One arm 179 of bail 176 extends upwardly, having an elongated pin 181 secured thereon engaging in a vertically disposed slot in the lever arm 156, while the other arm 182 of the bail 176 extends laterally through an aperture 183 in side frame member 13 for cooperation with a roller 184 carried on a disk 186 pinned on the leftmost actuator shaft 46. It becomes apparent, therefore, that with each rotation of the disk 186 an oscillation of the additive control lever arm 156 is effected. To control the oscillation of the subtractive control lever arm 164, an upwardly extending arm 187 of a bellcrank 178 carries an elongated pin 188 normally axially aligned with pin 181 and engaged in a vertically disposed slot in lever arm 164. The other arm 189 of the bellcrank 178 extends laterally through the aperture 183 in frame member 13 and is normally angularly displaced from arm 182 of the bail 176 for cooperation with a roller 191 on disk 186. The respective arms 189 and 182 lie in a plane adjacent opposite sides of the disk 186 and normally rest against

the hub of the disk extending beyond each side thereof. Arms 189 and 182 are resiliently maintained in engagement with the respective hub extensions of the disk 186 by means of a torsion spring 192 coiled counter-clockwise (FIG. 5) about the hub 177 of bellcrank 178 between the bellcrank 178 and arm 182, having its one end overlapping a pin 193 on arm 182 and its other end underlying a pin 194 on arm 189. Rollers 191 and 194, respectively, are carried on opposite sides of the disk 186 and are angularly displaced relative to each other, so that during the first part of each cycle of rotation of disk 186, each roller 184 and 191 engages the respective arms 182 and 189 to effect a simultaneous oscillation of lever arms 156 and 164, respectively, in opposite directions.

Subsequent to the oscillation of the lever arms 156 and 164 for the selective adjustment of the setting slide 135 and the additive or subtractive positioning of the tens-transfer bails 102 to 110, inclusive, relative to the corresponding disks 118, means are brought into play to rock the bail associated with the highest inboard order dial 23 and each of the bails to the left thereof, as viewed in FIG. 5. As explained above, the leg 122 of each of the bails 102 to 110, inclusive, is provided with an actuating arm 127 for controlling the rocking movement of the corresponding bail and all higher order bails. In each ordinally shifted position of the register carriage 20, the actuating arm 127 of the bail actively associated with the dial 23, which has become the highest inboard order dial, lies in a position to the left of the side frame member 13 (FIG. 5) for active cooperation with the rearwardly extended offset end of a dipper arm 196 (FIG. 3). Arm 196 forms one arm of a bellcrank 197 pivotally mounted at 198 on side frame member 13 and lies in a plane transversely of that of the actively positioned arm 127 of the corresponding bail. The vertically disposed edge of a depending arm 199 of bellcrank 197 is on the center line of the pivotal axis of the bellcrank and is maintained in engagement with a pin 201 on an upwardly extended arm 202 by means of a torsion spring 203. Arm 202 is integrally mounted with a cam follower lever arm 204 on the respective ends of a spacer sleeve (not shown) rockable about a stud 206 on side frame member 13.

In the full-cycle position of the parts (FIG. 3), a roller 207 on one arm of the cam follower lever 204 is in engagement with the peripheral surface of a cam 208 secured on the main drive shaft 50, whereby the extended end of the dipper arm 196 of bellcrank 197 is positioned above the plane of the laterally shiftable actuating arms 127 of the tens-transfer bails 102 to 110, inclusive. It will be recalled that the main drive shaft 50 is rotated once for each cycle of machine operation, including the operation of the shifting means to ordinally shift the register carriage 20 transversely of the machine. After approximately 220° counter-clockwise rotation of cam 208 (FIG. 3), the roller 207 on the cam follower arm 204 will, under certain conditions to be described hereinafter, be permitted to drop into an arcuate recess in the periphery of the cam 204 under the influence of the torsion spring 203 and the counter-clockwise rocking of the bellcrank 197. However, upon cyclic rotation of the cam 208 during a carriage shifting operation, the bellcrank 197 is retained in the inactive position shown in FIG. 3 against the urgency of the torsion spring 203. For this purpose, an ear 211 is formed at a right angle to the rearwardly extended arm of the cam follower lever 204 and normally underlies a square stud 212 on an upright arm 213 pivotally mounted on an extended pin 214 on the upper end of an arm 216 rockably mounted on a pin 217 on frame member 13. Thus, the roller 207 on cam follower 204 is prevented from dropping into the arcuate recess in cam 208.

If a machine operation, other than a shifting operation, is initiated, i.e., an operation involving the adjustment of the plus-minus gate 32 for positive or negative registrations in the register dials 23, the adjustment of

the gate 32 in the initial part of the cycle will effect removal of the square stud 212 from its engagement with the ear 211 of cam follower lever arm 204. A link 218 is pivoted at its one end at 219 on the left-hand arm 33 supporting one end of the plus-minus gate 32 and at its other end is pivotally mounted on the pin 214 on arm 216. Normally the square stud 212 is resiliently maintained in the centralized position shown in FIG. 3 by opposed arms 221 and 222 adjacently mounted for rocking movement on the pin 217 and spaced from arm 213 by the interpositioning of the forward end of link 218. A spring 223, secured at each end on an ear of the respective arms 221 and 222, normally urges the facing edges of the arms into engagement with diametrically opposed surfaces of the pin 214 and a pin 224 secured on arm 213 intermediate the ends thereof. It can be seen, therefore, that upon adjustment of the plus-minus gate 32 to engage either the plus gear 28 or minus gear 29 with the corresponding dial shaft gear 24, the arm 216 will likewise be rocked counter-clockwise, or clockwise, and the spring 223 will thereafter serve, through either arm 221 or 222, respectively, and pin 224 to rock arm 213 similarly, thereby moving the stud 212 rearwardly or forwardly of ear 211 on lever 204.

Although the stud 212 is moved out of blocking position relative to the ear 211, the roller 207 of lever 204 will remain in engagement with the peripheral surface of the cam 208, thereby retaining the bellcrank 197 in its inactive position for approximately 220° of the cycle. During this portion of the cycle, the rollers 191 and 184 on disk 186 become effective to adjust the setting slide 135 in accordance with the sign character of registration in the register dials 23. Subsequent to the adjustment of the setting slide 135, the torsion spring 203 rocks bellcrank 197, urging roller 207 into the recess in the periphery of cam disk 208. As it is rocked counter-clockwise (FIG. 3), the extended end portion of the arm 196 of bellcrank 197 engages the actuating arm 127 of the tens-transfer bail associated with the highest inboard order dial 23, rocking that bail and all bails to the left thereof in a clockwise direction.

Assuming the condition given hereinbefore wherein the carriage 20 is in the leftmost shifted position, the sign character setting slide 135 is in the adjusted subtractive position, as seen in FIG. 5, and the dials 23 register "0." The arcuate actuator fingers 126 of each tens-transfer bail 102 to 110, inclusive, will be actively aligned with the notches 120 (FIG. 6) in the disk 118 on the corresponding dial shaft 21. Thereafter, as bellcrank 197 is rocked, under the influence of spring 203, the arm 196 of the bellcrank rocks the actuator finger 126 of the tens-transfer bail 102 into the aligned notch 120 in the disk 118 associated with the highest inboard order dial 23. Simultaneously therewith, the actuator finger 126 on each of the tens-transfer bails to the left of the bail 102 will likewise be rocked into the aligned notch 120 in the corresponding ordinal disk 118.

Following the rocking of the actuator finger 126 of each of bails 102 to 110, inclusive into active position relative to the disk 118 associated with the corresponding dial 23, the subtraction of "1" in any keyboard order of the machine will cause the coordinate dial 23 to be rotated from "0" to "9," thereby initiating a tens-transfer, successively, in each higher inboard order dial 23. As the highest inboard order dial 23 passes from "0" to "9," the disk 118 associated therewith causes a lateral translation of the tens-transfer bails 102 to 110, inclusive, and setting slide 135 to the left in FIG. 5, thereby effecting a simultaneous rotation of the outboard order dials 23 from "0" to "9." The slide 135 will be resiliently retained in the left-hand adjusted position by toggle spring 147. It will be remembered that the left-hand position of the slide 135 is the additive position, so that if the following machine operation is of an additive sign

character the positive setting lever 156 will be idly rocked. However, if the succeeding machine operation is of a subtractive sign character, the rocking of the negative setting lever 164 will move the setting slide 135 and tens-transfer bails 102 to 110, inclusive, to the subtractive position thereof. Similarly, if the setting slide 135 is left in the subtractive adjusted position shown in FIG. 5, and the ensuing machine operation is of an additive sign character, the positive setting lever 156 will become effective to move the slide 135 to its left-hand position.

For a condition wherein the carriage 20 and the setting slide are positioned as shown in FIG. 5, but the sixteenth order dial 23, i.e., the fourth outboard order dial, registers a value other than "0," the arcuate actuator finger 126 of the tens-transfer bails 102 to 105, inclusive, will be rocked into the aligned notch in the disk 118 associated with the corresponding dial 23, whereas the radially disposed edge of the actuator finger 126 of bail 106 will enter the aligned radially disposed recess 119 in the disk 118 of the sixteenth order dial 23. Inasmuch as the radially disposed edges of the actuator fingers 126 form a helix circumferentially about shaft 111, the entry of the actuator 126 of bail 106 into a recess of the corresponding disk 118 precludes the active positioning of the actuators 126 of the higher ordinal bails 107 to 110, inclusive. Consequently, as the highest inboard order dial 23 passes from "0" to "9" upon the subtraction of "1," the thirteenth, fourteenth and fifteenth order dials 23 will be simultaneously rotated to "9," while the registration in the sixteenth dial will be decreased by "1." It becomes apparent that if, during a subtractive operation, the highest inboard order dial 23 or any of the higher outboard order dials 23 register a value other than "0," the actuator 126 of the corresponding bails will enter the aligned recess 119 in the associated dial disk 118, while the bail to the left of the actively positioned bail will remain inactive. In a similar manner, the actuator finger 126 of all the tens-transfer bails to the left of the highest ordinal actively positioned bail will remain inactive during an additive operation, if the actively positioned bail is engaged in an aligned recess 119 in the disk 118 associated with the highest order dial registering a value other than "9."

Upon shifting movement of the carriage 20, to the right from the position shown in FIG. 5, each of the outboard order dials 23 is ordinarily shifted inboard of the machine and thereafter comes under the control of the conventional tens-transfer mechanism. It is, therefore, necessary that each tens-transfer bail 102 to 110, inclusive, be disabled as the associated dial is ordinarily shifted to the right and becomes the next to the highest inboard order dial. For this purpose, a blocking member 225 is secured on the inside of the side frame member 13 (FIGS. 3 and 5), having its upwardly extended end formed at a right angle thereto and positioned in a plane parallel to the plane of shifting movement of the normally inactively positioned actuating arm 127 of the tens-transfer bails 102 to 109, inclusive. As each tens-transfer bail is shifted inboard of the machine, the actuating arm 127 thereof moves to a position overlying the blocking member 225 which prevents rocking movement of the corresponding bail and, because of the overlapping arrangement of the ear 126 of a lower ordinal bail with the ear 124 of the adjacent higher order bail, each bail to the right of the positively blocked bail is also disabled.

As explained hereinbefore, upon adjustment of the plus-minus gate 32 for an additive or subtractive operation, the square stud 212 is moved to the left or right of the ear 211 on lever 204 (FIG. 3), thereby permitting operation of the bellcrank 197 and arm 196. After approximately 220° of each cycle, the roller 207 on lever 204 drops into the recess in cam 208 and the ear 211 rocks to a position to the right or left of the square stud 212. The plus-minus gate 32 remains in its adjusted

position until near the end of the cycle of machine operation, whereupon it is restored in a well-known manner to the neutral position shown in FIG. 3. Substantially simultaneously, with the restoring of the plus-minus gate 32, the cam 208 rocks the lever 204 counter-clockwise, 5 raising the dipper arm 196 to its inactive position and moving the ear 211 to its normal position below the square stud 212.

From the above description of the preferred embodiment of the present invention, it can be seen that many advantages are inherent therein over the above-mentioned prior art, some of which have been mentioned herein and others which are obvious and need not be exemplified.

What we claim is:

1. In a calculating machine having

a frame,
a register carriage mounted for endwise shifting movement from one end position to another end position on said frame,

a plurality of ordinally arranged register wheels journaled in said carriage,
certain of said register wheels lying inboard of said frame and other of said wheels lying outboard thereof when said carriage is in its left end position,

means settable to control the sign character of registrations in said inboard register wheels,

a main tens-transfer mechanism within said frame operable to control an incremental transfer into said inboard register wheels,

and a cyclically operable power actuating means: an auxiliary tens-transfer mechanism mounted in said carriage operable for effecting tens-transfer into said outboard register wheels comprising the combination of

a rod supported in said carriage for axial adjustment to either of two positions, relative to the carriage, in accordance with the sign character of registrations in said inboard register wheels;

a plurality of tens-transfer bail-like actuators ordinally arranged relative to said outboard register wheels, and abuttingly mounted for rockable and non-slidable movement on the said rod;

an overlapping means on each lower order tens-transfer bail actuator being in cooperative relationship with an adjacent higher tens-transfer bail actuator whereupon a rocking movement of a lower order bail influences a corresponding rocking movement of an adjacent higher order bail;

a power-actuated positionable means rendered operable by said settable means to selectively adjust said rod to either of its two positions;

a series of auxiliary tens-transfer integrally constructed gear-disks, one associated with each of the said outboard register wheels and one associated with the highest order register wheel of the said inboard register wheel, each of said tens-transfer integral gear-disks having a notch therein representative of the "0" or "9" position of its associated register wheel and operable for engagement by the corresponding tens-transfer actuator upon rocking movement thereof during the subtractive or additive adjustment, respectively, of said rod;

a normally inoperative power operated resilient actuating means spaced from and aligned with the lowest order of the outboard tens-transfer bail-like actuators and operable to rock said actuators into the notches aligned therewith, in timed relation to the operation of said main tens-transfer mechanism to whereby an incremental transfer into the highest inboard register wheels transmits a similar transfer into the outboard register wheels upon axial adjustment of said rod;

and a disabling means aligned with and spaced from the highest inboard register wheel in a plane parallel to the plane of shifting movement of the inactive positioned tens-transfer bail-like actuators for positively preventing a rocking movement of any of those tens-transfer actuators that have been moved inboard of said frame upon shifting movement of said register carriage toward the right end position thereof.

2. In a calculating machine having a frame, a carriage mounted for endwise shifting movement from one end position to the other end position on said frame, a plurality of ordinally arranged register wheels journaled in said carriage, certain of said register wheels lying inboard of said frame and others lying outboard thereof when said carriage is in a left end position, means settable to control the sign character of registrations in said inboard register wheels, a main tens-transfer mechanism arranged within said frame operable to effect an incremental transfer into said inboard register wheels, and a cyclically operable actuating means: an auxiliary tens-transfer mechanism mounted on said carriage operable to effect an incremental transfer into said other of said ordinal register wheels comprising the combination of an auxiliary tens-transfer gear-disk connected to the highest order inboard register wheel and one connected to each of said outboard register wheels, each of said auxiliary tens-transfer gear-disks having a tens-transfer notch therein representative of the "0" registering position of the associated register wheel, a rod supported on said carriage for endwise adjustment to either of two positions in accordance with the sign character of a registration in said inboard register wheels, a plurality of tens-transfer actuating bails ordinally disposed relative to said outboard wheels and adjacently mounted for rockable and non-slidable movement on said adjustable rod, each of said tens-transfer actuating bails having a first portion thereof in cooperative relationship with a second portion of an adjacent tens-transfer actuating bail whereby a rocking movement of any tens-transfer actuating bail effects a rocking movement of the tens-transfer actuating bail associated with the adjacent higher order register wheel, each of said tens-transfer actuating bails including a tens-transfer actuating member angularly displaced relative to each other to form a helix circumferentially about said rod and operatively positioned for engagement in the notch of the corresponding gear-disk upon rocking of the associated actuating bail, a positionable means rendered operable by said settable means to selectively adjust said rod to either of its two positions, a drive means operated by said cyclically operable actuating means for controlling the operation of said positionable means subsequent to the adjustment thereof by said settable means, means normally biasing said tens-transfer actuating bails to an inoperative position in either adjusted position of said rod, a tens-transfer actuator operable to rock said normally inoperative tens-transfer actuating bails in timed relation to the operation of said main tens-transfer mechanism thereby moving the said tens-transfer actuating member successively into engagement with the notch of the corresponding ones of said tens-transfer gear-disks to mechanically continue a tens-transfer operation into said outboard register wheels upon operation of the main tens-transfer mechanism and an incremental transfer into the highest order inboard register wheel, and a blocking means for preventing the rocking movement of certain of said tens-transfer actuating bails as the corresponding register wheels are moved inboard of said frame upon shifting movement of said register carriage toward an end position thereof.
3. In a calculating machine having a frame, a shiftable carriage mounted for endwise shifting movement from one end position to the other end position on said frame, a plurality of ordinally arranged register wheels journaled in said carriage, certain of said register wheels

lying inboard of said frame and others lying outboard thereof when said carriage is in a left end position, a plus-minus gate movable in opposite directions from a neutral position to selectively control the sign character of registrations in said inboard register wheels, a main tens-transfer mechanism situated within said frame and operable to control an incremental transfer into said inboard register wheels, and a cyclically operable power actuating means: the combination comprising a rod mounted on the said carriage for endwise adjustment to either of two positions relative to said carriage in accordance with the sign character of registrations in said inboard order register wheels, a plurality of tens-transfer actuating bails, one for the highest inboard order register wheel and one for each of the said outboard order register wheels, each of said tens-transfer actuating bails including a first leg and a second leg, a lug on said first leg, an ear on said second leg, said actuating bails being adjacently mounted for rockable and non-slidable movement on said rod whereby said lug on said first leg of the actuating bail correlated to a higher order register wheel is cooperatively related to said ear on said second leg of the actuating bail associated with an adjacent lower order register wheel for enabling a rocking movement of the higher order actuating bail upon rocking movement of the adjacent lower order actuating bail, an arcuate tens-transfer actuating finger on said first leg of each of said actuating bails, said arcuate actuating fingers being equiangularly displaced relative to each other and operable upon rocking movement of said actuating bails to control an incremental rotation of the corresponding register wheels, means positionable by said plus-minus gate for adjusting said rod to either of its two positions, a power-driven means operated by said cyclically operable power actuating means to effect operation of said positionable means in timed relation to the positioning thereof by said plus-minus gate, spring means normally urging said tens-transfer actuating bails to an inoperative position in either adjusted position of said rod, a plurality of

auxiliary tens-transfer gear-disks associated with the highest inboard order of said register wheels and each of the said outboard order register wheels, each of said auxiliary tens-transfer gear-disks having a tens-transfer notch therein operable in the "9" or "0" registering position of the associated register wheel, to be engaged by the corresponding one of said tens-transfer actuating fingers upon rocking movement thereof subsequent to the respective additive or subtractive adjustment of said rod, 5 a spring-actuated tens-transfer enabling dipper operative to rock said tens-transfer actuating bails against the resistance of said spring means, a blocking means normally operable to prevent operation of said spring-actuated tens-transfer enabling dipper, means controlled by the 10 operation of said plus-minus control gate to disable said blocking means, a cam means driven by said cyclically operable power actuating means effective to maintain said tens-transfer enabling dipper inoperative subsequent to the operation of said disabling means and operable 15 in timed relation to the operation of said main tens-transfer mechanism to enable operation of said spring-actuated tens-transfer dipper whereby the said tens-transfer actuating fingers are successively rocked into engagement with the notches in the corresponding gear-disks to 20 mechanically continue a tens-transfer operation into the said outboard order register wheels upon operation of said main tens-transfer mechanism and an incremental transfer into the highest inboard order register wheel, and a blocking member for preventing the rocking movement of certain of the said other of said tens-transfer actuating bails as the corresponding register wheels are moved inboard of said frame upon shifting movement of said 25 register carriage toward an end position thereof.

UNITED STATES PATENT OFFICE
CERTIFICATE OF CORRECTION

Patent No. 3,022,947

February 27, 1962

Vito Viola et al.

It is hereby certified that error appears in the above numbered patent requiring correction and that the said Letters Patent should read as corrected below.

Column 1, line 20, for "acuating" read -- actuating --; column 3, line 9, for "wihtin" read -- within --; line 65, for "geras" read -- gears --; column 5, line 2, for "constitue" read -- constitute --; column 7, line 1, for "ordinarily" read -- ordinarily --; column 8, line 9, for "move" read -- more --; line 24, for "convention" read -- conventional --; line 51, for "identations" read -- indentations --; column 9, line 2, for "chamfered" read -- chamfered --; column 11, line 47, for "counterclockwise" read -- counter-clockwise --; column 12, line 8, for "194", second occurrence, read -- 184 --; column 13, line 59, after "inclusive" insert a comma; column 15, line 28, for "sail" read -- said --; column 16, line 4, for "positvely" read -- positively --; column 17, line 1, for "lyong" read -- lying --.

Signed and sealed this 27th day of November 1962.
